UNITED STATES PATENT OFFICE.

JOHN A. MACDONALD, OF BOSTON, MASSACHUSETTS.

SEPARATOR OR AMALGAMATOR.

1,237,798.

Specification of Letters Patent. Patented Aug. 21, 1917.

Application filed December 13, 1915. Serial No. 66,610.

To all whom it may concern:

Be it known that I, JOHN A. MACDONALD, a citizen of the United States, residing at Boston, in the county of Suffolk and State 5 of Massachusetts, have invented new and useful Improvements in Separators or Amalgamators, of which the following is a specification.

This invention relates to separators or 10 amalgamators for the separation of gold and other precious minerals from materials bearing the same and the amalgamation of the extracted mineral.

The main object of the invention is to 15 provide a combined separating and amalgamating apparatus wherein the ores, if containing coarse values, may be subjected to a mechanical separating action for the extraction of the coarse values and subsequently subjected to an amalgamating treatment 20 for the extraction of the fine values or wherein the ores may be treated to a series of amalgamating actions when containing only fine values or an amalgamating process throughout is required.

A further object of the invention is to provide a separatory apparatus which is simple of construction, reliable and efficient in action, and by means of which the materials 30 may be treated as required for the efficient extraction of their mineral contents.

The invention consists of the features of construction, combination and arrangement of parts herein fully described and claimed, 35 reference being had to the accompanying drawings in which:—

Figure 1 is a side elevation of a separatory apparatus constructed in accordance with my invention.

Fig. 2 is a central, vertical, longitudinal section of the same.

Fig. 3 is a sectional plan view on the line 3—3 of Fig. 1.

Fig. 4 is a vertical transverse section on 45 the line 4—4 of Fig. 1.

Fig. 5 is a view showing the manner of connecting the inlet ends of the flush pipes with the water or air service pipes.

Fig. 6 is a detail vertical section showing 50 a modified form of regulating valve for use under some conditions.

Figs. 7 and 8 are vertical sections, taken at right angles to each other, through the automatic feeder.

Referring to the drawings, 1, 2 and 3 55 designate a series of separatory devices, of

which any suitable number may be employed, three being shown in the present instance for purposes of exemplification. The separatory devices are arranged in stepped or gradient relation, at different levels, and are supported upon a suitable base or foundation 4, the separatory device 1 arranged at the highest level being the first in order in the series, and the separatory device 3 arranged at the lowest level the final in order in the series.

Each of these separatory devices comprises a body 5 formed to provide an agitating or amalgamating chamber 6 having a bowl-shaped bottom or basin 7 forming a receptacle for the material under treatment or for the amalgamating substance 8, such as mercury, when such substance is used. The chamber 6 is provided with a removable cover 9 having an inlet 10 for the introduction of the mercury, and each body 5 is detachably secured to and supported upon a hollow standard or pedestal 11 having an outlet 12 for the discharge of the mercury from the bowl or basin, said outlet communicating with the bottom of the bowl through a discharge passage 13. A valve or cut-off plate 14, movable on a wheel or roller bearing 15, is provided to normally close the passage 13, and said valve is movable to open and closed positions by means of an exteriorly projecting handle 16. A locking device 16^a, of suitable construction, may be provided for normally holding the valve 14 closed, so that it can only be opened by an authorized person.

The separatory devices 1 and 2 are each provided with an inlet 17 for the introduction of the pulp into its chamber 6 above the level of the mercury, and a hopper or feed nozzle 17', communicates with the opening 17 of the separatory device 1 for the introduction of the pulp thereto.

In employing the separatory devices 1 and 2 for amalgamating actions, the bowl 7 of each of said devices may be filled with mercury up to the level indicated by the line $x-x$ when the apparatus is working at full capacity, and to the lower level indicated by the line $y-y$ when the apparatus is operated at its lowest speed and capacity. At one side the bowl 7 is provided with drain outlets 18 and 19 communicating with valves or faucets 18' and 19', arranged at or slightly above the mentioned levels of the mercury, for the withdrawal of the water and tailings

from the amalgamating chamber. At its opposite side above the level of the line $x-x$, each chamber 6 is provided with a pulp discharge outlet 20, the passages 20 of the separatory devices 1 and 2 being in communication with outlet connections 21 and 22, respectively, while the outlet passage 20 of the separatory device 3 communicates with a tailings discharge spout 23. The passage 10 20 of the first separatory device 1 is in communication with the inlet 17 of the second separatory device 2, and, if desired, more than two separatory devices, like the devices 1 and 2, which differ somewhat in construction 15 from the separatory device 3, may be employed, in which event the outlet 20 of the separatory device 2 will communicate with the outlet of the next separatory device of the same type in order in a series, as will 20 be readily understood. In the present instance, however, I have shown the connection 22 communicating with the outlet 20 of the separatory device 2 arranged to connect with a discharge nozzle 24, designed for 25 a purpose hereinafter described.

The separatory devices 1 and 2 may be employed for either mechanical separation, in which the gold is separated from the pulp by gravity, or for amalgamating actions, using 30 a suitable amalgamating agent, such as a body of mercury 8, as before described. When a strictly mechanical separating action is employed, which may be advantageously used where the ores contain coarse 35 values, the pulp, together with a supply of water, is fed to the chamber 6 of the separator 1 and subjected to agitation so that the particles of gold which are freed by the agitation or washed out by the water will descend 40 by gravity to the bottom of the chamber, while the pulp and lighter particles of the mineral will pass off finally through the outlet of the separator 1 into the separator 2, in which they may be subjected to the same 45 treatment, by which gold of the next coarse grade will be separated, the pulp and fine values finally discharging from the outlet of the separator 2 and being then transferred to the separator 3, where they are subjected 50 to a final amalgamating action for the separation of the fine values. If desired, however, all of the separators may be employed as amalgamators, in which event it will be understood that the pulp entering the chamber 55 6 of the separator 1 will be agitated and a proportion of the gold taken up by the body of mercury 8, the pulp finally rising to the level of the outlet 20 and passing to the separator 2, where a second amalgamating 60 treatment is carried out, the pulp thence passing to the separator 3 where the finer values are amalgamated and the tailings finally discharged as refuse, as will be readily understood. That portion of the wall of 65 each chamber 6 between the outlet 20 and

maximum level line $x-x$ of the mercury acts as a baffle or retarder to prevent the discharge of the pulp from the chamber 6 until it reaches a predetermined level therein.

Arranged within the chamber 6 of the 70 separators are rotary agitators 25 each mounted upon the lower end of a vertical shaft 26 which is journaled in and extends outwardly through a stuffing box 27 on the cover 9. The upper end of this shaft carries 75 a collar or thrust bearing member 28 rotating in contact with the anti-friction bearing balls 29, and suitably fixed to said bearing member and shaft is a beveled gear 30. The gears 30 of the two separator agitators mesh 80 with drive gears 31 on a line shaft 32 journaled in suitable bearings 33 on the covers of the respective separator devices, 1, 2 and 3. This shaft may consist of one or more sections suitably coupled together, and on said shaft is a pulley 34 by which it may be driven from a suitable source of power. Through the rotation of the shaft the agitators are driven to stir the mass under treatment for mechanical separation or agitation 85 of the pulp and mercury to thoroughly expose the particles of the pulp to the mercury for an amalgamating action before the pulp is allowed to pass off.

The outlets 20 are controlled by vertically 90 movable gates or valves 35, each of which is connected at its upper end with a crank or wrist pin 36 on a gear 37 receiving motion from a pinion 38 on the shaft 32, whereby 95 in the rotation of the shaft the valves 35 will be opened and closed once on each rotation thereof. These valves govern the discharge of the pulp through the outlets 20 and are geared for operation in timed accord with the agitators, so as to insure a 100 proper agitation of the mass before the pulp is allowed to pass off, the gates being operated intermittently and simultaneously with each other, while the agitators continuously 105 revolve.

For the purpose of flooding or flushing the amalgamators with water to wash out the tailings previous to drawing off the amalgam or deposited mineral matter, I provide water supply pipes 39 extending along opposite 110 sides of the separators and having branches 40 leading therefrom into the chambers 6, and three-way valve 41 for controlling the flow of water through the pipes and branches. The pipes are connected at one end by a 115 union 42 with one or more service pipes 43 having controlling valves 44. Instead of supplying water through these pipes to the separators, they may be employed for the purpose of introducing compressed air under 120 a suitable degree of pressure, by which the material within the separators may be either agitated or the pulp blown out.

It will be understood from the foregoing 125 description that in the operation of the ap- 130

paratus or carrying out successive amalgamating steps of treatment the amalgamating chambers are charged with mercury through the inlets 10, the pulp to be treated fed in any suitable manner to the primary separator and the drive gearing set into action to actuate the agitators and regulating valves. The pulp entering the primary separator is agitated together with the mercury therein, whereby the mercury is thoroughly commingled with the pulp and takes up a certain proportion of the gold or other precious metal contained therein. The pulp rises in the chamber 6 until it reaches the level of the outlet 20, through which it discharges and enters the amalgamating chamber of the next separator 2 through the passage 21, the discharge of the pulp from the amalgamating chamber of the separator 1 being temporarily retarded by the valve 35, which opens at predetermined intervals to allow the pulp to pass out. The pulp deprived of a portion of the mineral is treated in like manner in the amalgamating device 2 and finally discharges therefrom through the spout 24 and is delivered to the separator 3 in which amalgamation of the finer particles of the mineral is effected, the free tailings discharging through the final outlet 23 of said separator 3. This operation is continued until a determined amount of the pulp has been treated and the mercury contained in each of the separators has taken up a maximum amount of the gold or other metal, at which time the feed of fresh pulp to the primary amalgamating device is arrested and the valves 41 opened to admit water into the amalgamating chambers for the purpose of flushing the same and washing the tailings remaining in the separators at such time, the tailings and water being drawn off through the faucets 18' and 19'. After this is effected, the gates or valves 14 are then opened for the withdrawal of the amalgam through the outlets 12, as will be readily understood. As before stated, a current of air supply through the pipes 39 may be employed to agitate the pulp and mercury, and if desired the mercury may be withdrawn from the separators 1 and 2 when the material contains coarse values and the separation effected by the agitation of the mass so as to free the coarse particles of gold which feed downward by gravity to the bottom portions of the chambers 7, from which they may be withdrawn and collected after discharge of the pulp, the pulp being finally treated in the separator 3 for the extraction and amalgamation of the finer values. The gates or valves 35 may be imperforate, as shown in Figs. 1 to 5, inclusive, but if desired, perforated screen valves 35^a of the form shown in Fig. 6 may be employed for dry separation, such as valves allowing a certain amount of the drier gangue or pulp to pass off in the closed position of the valves, so that a more rapid separating action can be effected. The pulp passing after the second stage of treatment through the nozzle 24 drops into the receptacle 45 communicating through a suction pipe 46 with the inlet of the casing of a suction and discharge fan or pump 47, from the outlet of which pump casing the material is discharged and delivered through a nozzle 48 into the bottom of the chamber of the separator 3 below the level of the mercury therein, whereby the material and mercury are agitated and commingled so that a thorough exposure of all particles of the pulp to the mercury will be effected, resulting in the extraction and amalgamation of the finer values, the amalgam being drawn off finally through the outlet 12 of said separator and the tailings discharged through the nozzle 23. The pump shaft carries a pulley 49 which is driven by a belt 50 from a pulley 51 on the line shaft 32.

It will thus be seen that my invention provides a separating apparatus whereby separation may be effected by gravity or amalgamation, and wherein provision is made for final amalgamation of the finer contents of the bearing material. Also that owing to the means for producing a thorough agitation a maximum degree of separation and extraction of the gold will be effected, and that the efficiency of the apparatus is greatly increased by the use of the automatic regulator valves controlling the discharge of the pulp. By the use of the water flush or air pressure pipes the material may be additionally agitated and the separators flushed out and cleansed whenever required, while by the described mode of delivering the pulp to the final separator simplicity is insured, and greater efficiency obtained, since the feeding material is agitated under its feed motion and the mercury agitated thereby so as to thoroughly expose all particles of the pulp to the action of the mercury.

If desired, an automatic feeder of suitable construction may be employed for supplying the pulp to the hopper 17'. As shown in the present instance a rotary type of feeder is disposed in position above the hopper and comprises a casing 52 suitably fastened in place and provided with an inlet 53. Arranged within the casing below said inlet is a bladed or pocketed feed wheel 54 mounted upon a shaft 55 provided at one end with a pinion 56. On the shaft 55 are guard disks 57 which project into a groove formed by a guard flange 58 at the bottom of the inlet 52, whereby the pulp is guided between the blades or into the pockets of the wheel and prevented from getting between the wheel and the sides of the casing and causing binding or choking of the feed de-

vice. The pinion 56 meshes with a gear 59 on a shaft 60 provided also with a beveled pinion 61 meshing with the adjacent gear 30, by means of which the feeder will be 5 driven automatically from the line shaft with the other working parts of the apparatus. In practice, the drive pulley 34 may be mounted either on the shaft 32 or on the shaft 60, as desired.

10 I claim:—

A separating apparatus comprising a separating chamber having an outlet, a closed receptacle forming a suction box in communication with said outlet, a second 15 separating chamber having an amalgamat-

ing basin, a nozzle extending into said basin below the level of the outlet, a conductor having suction and discharge portions, respectively connected with said suction box and the nozzle, and a suction and force 20 pump arranged in said pipe between said suction and discharge portions, for sucking the material from said suction box and delivering the same to said nozzle.

In testimony whereof I affix my signature 25 in presence of two witnesses.

JOHN A. MACDONALD.
